FIBER CUTTING MACHINE

Fred R. Zimmerman, Chicago, Ill., assignor to
Nachman-Springfield Corporation, Chicago,
Ill., a corporation of Illinois

Application August 9, 1937, Serial No. 158,041

2 Claims. (Cl. 164—61)

The present invention relates to machines for cutting long fiber into substantially predetermined lengths to fit them for incorporation into upholstery batts.

- 5 The main object of the invention is to provide a machine of this character which will cut long fibers simultaneously into a number of separate pieces each of substantially predetermined length and thereafter delivering the same upon a conveyor belt for distribution to a conventional machine known as a "picker" which picks the relatively compact masses of the fiber apart and delivers the same to other machinery commonly employed in the production of upholstery batts.
- 10 15 A further object of the invention is to provide a machine of the type indicated which is power-actuated and is so constructed and arranged that the operator who feeds the fiber into the machine cannot bring his hands or fingers into contact with the cutting elements and wherein an attempt by the operator so to do will actuate means whereby the operation of the machine is interrupted.
- 20 25 A suitable embodiment of the invention is illustrated in the accompanying drawings, wherein

Fig. 1 is a front elevation, partly in vertical section, of a fiber cutting machine constructed in accordance with the invention.

- 30 Fig. 2 is a side elevation of the same.
- The fibers used for some classes of upholstery batts are composed of sisal, jute or similar fibers, or a mixture of several thereof, which are used ordinarily in the manufacture of rope, twine, burlap and similar products. These fibers are baled and have an average length of several feet each. In the bales the fibers extend in one general direction so that upon removing the bale ties the bale may be easily divided into slabs of any desired thickness and are of the width and length of the bale. The upholstery batts composed of this type of fiber are made by means of carding machines and camel back lappers and the long fibers have a tendency to wind themselves about the drum of the carding machine, which is commonly known as a "Garnet" machine in the art. The long fibers are also ill adapted for the action of the camel back lappers and, therefore, it is desirable that said fibers be cut to lengths ranging from a minimum of about nine inches to a maximum of about twelve inches, depending upon the particular type of fiber employed, an appreciable percentage of shorter fibers being included in the mass commingled and relatively evenly distributed among the longer

fibers by the action of the aforesaid pickers and pneumatic conveying means which carry the cut fiber from the picker to the carding machines from which they are delivered to the said camel back lappers.

The cutting of the fibers has been effected in various ways as, for example, by means of band-knives and by shears which simulate paper cutting shears, both of which have proved very dangerous to operators who feed the slabs taken 10 from the bales into said cutting machines.

The machine of the present invention comprises a suitable frame 1 equipped with longitudinal guide slots 2 at diametrically opposite sides in which the bearings 3 of a shaft 4 are mounted, said bearings being adjustable longitudinally of the frame by means of the adjusting screws 5 and 6. Said shaft 4 is driven from a suitable source of power, such as an electric motor 7, suitably geared to the shaft 4 to rotate 20 the same at any desired predetermined speed. In the instance illustrated the gearing consists of pulleys and belt 8 trained over the same but it will be understood that any other desired type of gearing may be substituted for said pulleys 25 and belt.

Mounted upon the shaft 4 is a cylindrical drum 9 which is equipped with surface projections 10 and, as shown in Fig. 1, is also equipped at regular intervals with annular slots or recesses 11 which are spaced substantially equidistantly from each other and the outermost of which are spaced farther from the ends of the drum than the spacing of said slots from each other.

Disposed at an incline above the forward half-portion of the drum 9 is a feed table 12 upon which an operator deposits the bale slabs of fiber heretofore referred to and pushes them toward the drum, the said feed table or plate 12 being 40 disposed substantially tangential to the uppermost point in said drum. The front edge of the plate or table 12 is disposed at an elevation substantially equal to the height of the chest of the operator.

Mounted upon the rear end portion of the frame 1 is a pair of frame members 13 upon which an electric motor 14 is mounted. Said frame members 13 are equipped with bearings for the shaft 15 which is suitably geared to the motor 14 and 50 is parallel with the shaft 4 but disposed at a higher elevation and spaced appreciably rearwardly thereof. Mounted upon the shaft 15 is a plurality of circular cutting knives 16 which project in part into the annular recesses or slots 11 of the 55

drum 9 and which rotate in the direction opposite to the direction of rotation of the said drum 9 and at far higher speed.

Pivots mounted in brackets 17 carried by the 5 front edge portion of the plate or table 12 is a shaft 18. A plurality of bell crank levers 19 are rigidly mounted upon the shaft 18 at their elbow portions and are rigidly connected with each other by means of cross-rod 20 extending over 10 the entire width of the plate or table 12. Said rod 20 is disposed in the path of the chest of the operator so that if the latter leans against said rods, it will rotate the bell-crank levers about the pivotal axis of the shaft 18. The inner and 15 shorter arms 21 of the bell crank levers 19 normally maintain an electric switch 22 mounted upon the lower face of the plate or table 12 in position to close the electric circuits feeding the respective motors 7 and 14 so that in the event 20 that said bell-crank levers are swung about their pivotal axis, as aforesaid, the said electric circuits are opened immediately and the operation of the machine is thus interrupted.

A guard plate 23 is disposed over and in spaced 25 relation to the drum 9 at a point immediately forward of the cutting edges of the knives 16 and serves primarily to indicate the limit of thickness of the bale slabs which may be introduced into the machine and in the event that a bale slab 30 is of too great thickness will halt the same and prevent it being fed to the said knives 16, except as to such quantity of said fiber as may be pulled from the bottom of the slab by means of the 35 projections 10 of the drum, the slab being then gradually decreased in thickness so that it will pass progressively under said guard plate 23.

The slab of the bale of fibers is disposed upon the table or plate 12 so that the fibers extend substantially transversely of the direction of 40 travel of the slab into and through the machine. After deposit upon said plate the operator pushes the slab forward so that it will be caught by the drum and will then be fed to the said knives 16. It will be observed that the edges of the cutting 45 knives 16 meet the periphery of the drum at an acute angle and that both the drum and the knives tend to project the cut fiber downwardly so as to clear the drum of the same. After being cut the fibers fall by gravity upon the conveyor belt 24 which carries the cut fibers to the aforesaid picker.

Additionally to the means heretofore described 50 for preventing the operator from bringing his fingers into contact with the cutting knives 16, the machine will be equipped with high side plates, omitted from illustration herein, for preventing operator's access to the knives from the sides of the machine.

The rear plate 25 of the machine is removable 55 for the purpose of providing access to the cutting edges of the knives 16 for sharpening said knives when desired and to this end said plate 25 is hinged to the cross rod 26 joining the side frame members 13 at their upper rear corners. The plate 23 is similarly pivotally engaged with the cross rod 27 connecting the upper front corners of the members 13 with each other.

The machine of the present invention operates 60 to cut fibers more rapidly than has been true of the machines used heretofore and is desirable from the standpoint of safety as well as economy of operation.

By means of the screw engaged with the bearings of the shaft 4, the position of the drum 9 relatively to the cutting knives may be adjusted to vary the angular relation of the cutting edges of the said knives to the circumference of the 5 drum for purposes of promoting the efficiency of action and to prevent heating of the knives in event the fiber slabs are fed too rapidly and compactly to said knives especially when said knives become slightly dull. 10

In the instance illustrated the drum 9 is composed of sections of desired width which are interchangeable for sections of other widths, the knives being adjustable on the shaft 15 to position them to accord with the spacing apart of 15 the slots between the sections of said drum 9.

I claim as my invention:

1. A machine of the type specified comprising a series of parallel spaced apart rotatable cutting blades, a rotatable feed drum equipped 20 with annular slots of width appreciably greater than the thickness of the blades and into each of which a cutting edge portion of a blade projects free of contact with the walls thereof, said drum and blades being rotatable in opposite 25 directions and cooperating to effect downward travel of material subjected to their action, means for adjusting the relative positions of said drum and said blades, a feed table having its inner edge overhanging the uppermost portion of said 30 drum and opposed to said blades, a gauge device disposed over and spaced from the rear edge portion of the table for controlling the thickness of the batch of material capable of being fed to the blades, the radius of the latter being 35 appreciably greater than the said thickness of the batch as determined by said device for preventing contact of said material with any surfaces other than side faces of the blades and the circumferential face of the drum during its 40 passage through the cutting zone said drum being equipped with a plurality of surface projections for removing material from the lower part of the batch while the same is retarded by said gauge device to thin the batch until it can be 45 fed further over the feed table, the rear edge of said table spaced more than an arm's length from said blades and power means for actuating the said blades and said drum.

2. A machine of the type specified comprising 50 a rotatable drum composed of spaced apart sections, rotatable cutting knives projecting into the spaces between said drum sections, means for causing the said knives and the drum to rotate in opposite direction for cooperation with each other to cut material and cause downward passage thereof, lugs on the circumferential faces of the drum sections to effect forced movement of material toward the blade edges, a feed table over which the material is passed into engaging relation to said drum, a gauge device disposed over and spaced from said table for regulating the thickness of the batch of material capable of being fed to the drum and cut by said blades, said lugs adapted to remove material from the bottom of a batch halted or retarded by said gauge device for reducing the depth of the latter to the degree requisite to effect passage of the remainder of the batch past the said gauge device. 60 65

FRED R. ZIMMERMAN. 70
